UNITED STATES PATENT OFFICE.

CLEON M. HANNAFORD, OF RICHMOND, VIRGINIA, ASSIGNOR TO CAR DEVICES COMPANY, OF RICHMOND, VIRGINIA, A CORPORATION OF VIRGINIA.

FRONT DRAFT LUG.

Application filed May 22, 1925. Serial No. 32,059.

This invention is in the nature of a modification of or improvement upon the front draft lug forming the subject of the application of Arthur H. Weston, filed February 20, 1925, Serial No. 10,617, Patent No. 1,551,353, dated August 25, 1925.

The invention herein consists in extending the plate or body of the lug in the direction of the length of the rear extension, thereby furnishing riveting surfaces adjacent to the rear extension, as I will proceed now to explain and finally claim.

In the accompanying drawings illustrating the invention, in the several figures of which like parts are similarly designated, Figure 1 is a top plan view, partly in horizontal section, illustrating enough of the center sill and adjacent parts to show the application of the present invention, and Fig. 2 is a side elevation with the end sill in cross section. Fig. 3 is a plan view, in elevation, of the front draft lug detached; Fig. 4 is an edge view, and Fig. 5 an end view developed from Fig. 3.

Without thereby limiting the invention to any particular form of draft rigging or draft sills or center sills, the invention will be described, by way of illustration, in connection with a center sill made up of two metal channel beams, set with their webs upright and in parallelism and spaced apart sufficiently to admit the draft gear.

The channel beams have the bottom flanges 1, top flanges 2, and webs 3, all of any usual or approved construction, and have their webs slotted longitudinally, as indicated at 4, to permit the ribs of the front draft lugs, hereinafter particularly described, to extend through and beyond the said webs.

5 is the outer portion of an ordinary yoke, 6 is the shank of the coupler, 7 is the striking plate, and 8 is the draw-bar carrier, all of ordinary or approved construction.

The invention herein is not limited to these details, and is adaptable to other constructions.

The front draft lug of this invention comprises a plate or body 9, having the side shown uppermost in Fig. 4 as a substantially flat surface, but provided with the longitudinal ribs 10, parallel with an intermediate slot 11, and surrounding the inner end of said slot, so that the lug may be fitted flat and snug against the inside surface of the web of the center sill, with the ribs extend-

ing through the slot 4, and said ribs projecting outside of the web. These ribs are extended at 12 beyond the end of the body of the lug, and such extension enters the slot in the web, thereby serving to align the parts and transmit strains to the center sill. The lug is provided with the transverse projection 13 on the opposite or inner side, so as to form an abutment for the front follower 14. This projection or abutment 13 preferably is reinforced by the inclined ribs 15, and there are similar ribs 16 at the longitudinal edges of the lug which extend back to and reinforce the abutment 13.

The plate 9 extends not only laterally beyond the slot and its ribs 10, but also extends forwardly at 17 so as to completely overlie the slot in the web of the center sill.

The front draft lug may be secured to the web of the center sill by any suitable means, preferably rivets 18, applied through the series of holes 19.

The plate or body 9 is continued at 20 so as to surround the extension 12 and lap over upon the web of the center sill member 21 around the slot in said web in which the extension 12 is located. This continuation 20 is in the nature of a reinforcement and affords a surface and holes for four additional rivets 21, the heads of which are countersunk 22 in the continuation, as indicated by the dotted lines 22 in Fig. 1, so as not to interfere with the operation of the front follower.

This continuation 20 is integral with the other parts of the front draft lug, and as stated, serves as a reinforcement for the extension 12 in its engagement with the slot in the web of the center sill member, and constitutes the modification or improvement forming the subject of this case.

The front draft lug may be conveniently made as a single unitary casting, and preferably of steel.

One of these lugs is secured to each of the center sill members on the inner side thereof, and when the coupler and yoke are placed in position between them, they are secured by means of any suitable transverse key 23, preferably headed at 24 on one end and provided with a hole 25 at the other end to receive a cotter-pin or other fastening means.

The slots 11 in the lugs are made sufficiently large to allow for necessary motion of the draft gear, and so that in buffing the transverse key will abut against the extended

surfaces of the lugs, the strain being taken off of the rivets practically by the solid or unslotted rearward extension 12.

The front draft lugs of this invention are intended to take the place of the front draft lugs heretofore used, same being a component part of all draft arrangements, inclusive of vertical plane yoke and friction draft gear.

10 The lug of this invention has all of the advantages of the lug of the application referred to, in addition to the reinforcing feature.

15 Variations in the details of construction are permissible within the principle of the invention and the scope of the claims following.

What I claim is:—

1. A front draft lug, having a body adapted to be applied to the inner side of a longitudinally slotted center sill member, and provided with a longitudinal slot to receive a coupler key, a rear extension adapted to engage the slot in the sill member, and a continuation of the body of the lug beyond said rear extension said continuation in one piece with the body and provided with holes to receive means for attaching it to the sill member.

2. A front draft lug, having a body slotted longitudinally and adapted to be applied to the inner side of a longitudinally slotted center sill member and provided with a rib flanking the sides of the slot and its rear end and extending rearwardly beyond said slot and adapted to engage the longitudinal slot in a center sill member, said rearward extension being flanked by a continuation of the body of the lug beyond the sides and rear end of the rib.

3. The combination with center sill members provided with longitudinal slots, of front draft lugs applied on the inner sides of said center sill members and slotted longitudinally and provided with ribs flanking the sides and inner ends of the slots in the lugs and extending rearwardly and solidly beyond the slots in the lugs and fitted in the slots in the center sill members, said lugs having continuations flanking the said rearward extensions beyond the sides and rear ends of the ribs and provided with countersunk holes for rivets for securing the lugs to the center sill members.

In testimony whereof I have hereunto set my hand this 21st day of May A. D. 1925.

CLEON M. HANNAFORD.
